UNITED STATES PATENT OFFICE.

ODE TURNER, OF POTTER, ARKANSAS.

GASOLINE-VENDING MACHINE.

Application filed August 10, 1925. Serial No. 49,484.

The invention relates to gasoline vending machines, and has for its object to provide a device of this character adapted for use in connection with a conventional form of gasoline dispensing and measuring device and provided with coin controlled mechanism for controlling a valve, and by means of which mechanism gasoline having a sales value according to the denomination of the coin placed in the device, may be discharged from the device.

A further object is to provide a coin controlled gasoline vending machine which may be operated upon the insertion of a coin therein for dispensing gasoline to the value of the coin, and which will eliminate the necessity of maintaining an operator for the device.

A further object is to provide the supply pipe with a valve having a control arm and float control means for automatically closing the valve after an operation thereof, which operation is controlled by a coin placed within the machine.

A further object is to provide a spring motor operating shaft and provided with detent means coin controlled, and which shaft is provided with an arm which cooperates with the valve controlling bar for moving the valve to open position when the detent coin controlled means is tripped, and means for allowing a single revolution of the shaft and its arm.

A further object is to provide a vertically movable frame to which the float is connected by means of a rod and a plurality of vertically disposed shafts rotatably mounted in the frame, and which shafts are provided with arms normally in registration with the coin slots where said arms will be engaged by coins and the shafts rotated substantially ninety degrees when a coin is forced through any of the slots. Also to provide detent means for holding the shafts in operative positions after a rotation thereof whereby pins carried by the shafts will engage and release the valve control bar upon an upward movement of the frame. The pins are positioned according to the amount of gasoline desired to be vended for the particular amount of coin placed in the device.

A further object is to provide an adjustable connection between the float carried rod and the frame whereby the pins may be varied in position in relation to the valve

operating bar which allows adjustment of the device incident to fluctuation in price of gasoline.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawings:

Figure 1 is a front elevation of the device, parts of the casing being broken away to better show the structure.

Figure 2 is a detail perspective view of a portion of the slidable frame showing one of the rods in an operative position.

Figure 3 is a vertical transverse sectional view through the valve.

Figure 4 is a vertical transverse sectional view taken on line 4—4 of Figure 1.

Figure 5 is a detail collective perspective view of the main coin chute and the coin receiving end of the trip lever.

Figure 6 is a top plan view of the tripping mechanism showing a portion of the casing in horizontal section.

Figure 7 is a sectional view taken on line 7—7 of Figure 6.

Figure 8 is a perspective view of the trip lever.

Referring to the drawing, the numeral 1 designates the casing of a conventional form of gasoline dispensing device as at present in use, and supported on the upper end of the casing 1 is a glass container 2, into which gasoline is pumped in the usual manner through the pipe 3. The gasoline is discharged from the container 2 through the discharge pipe 4 and hose 5 in the usual manner, therefore it will be seen that the dispensing device may be used and manually operated for dispensing liquid without the coin control mechanism as hereinafter set forth if desired. However the normal using of the device may take place after the operator has rotated the valve 6 to a position where it will not stop the flow of gasoline through the pipe 3 during the pumping operation.

One side of the casing 1 is provided with an auxiliary casing 7, and in which auxiliary casing is slidably mounted a frame 8, which frame is rectangular shaped and comprises

side bars 9, an upper bar 10 and a lower bar 11, therefore it will be seen that the frame is 5 rectangularly shaped. Rockably mounted in the frame 8 are vertically disposed shafts 12, 13 and 14, which shafts extend upwardly through the frame to one side of the coin receiving slots 15, and are provided with arms 16, which normally register with the slots 15 and form closures therefor, and 10 which arms are held in registering positions, by means of coiled springs 17, which are anchored to the shafts at 18 and to the frame 8 at 19, therefore it will be seen that when a coin is inserted in any of the slots 15 the 15 rock shafts will be rocked according to the denomination of the coin inserted, which action will cause any of the pivoted arms 20 to be moved inwardly up to the inclines 21 carried by the lower bar 11 of the frame 20 and the pivoted arm 20, which is carried by the shaft which has been operated, will drop behind the shoulder 22 carried by the bar 11, and will hold said shaft against retrograde rotation, and will hold the pin 23 25 of the particular operated shaft in an outwardly extending position, substantially at ninety degrees to its normal position, where the operated pin will engage the valve control lever 24 upon an upward movement of 30 the frame 8 as a whole. After the coin passes through the coin receiving slots 15, it enters one of the troughs 25, then into a hopper 26, therefore it will be seen no matter what denomination the coin may be 35 it will enter the same hopper 26. Valve 6 is normally maintained in closed position by means of the spring 27 which is anchored to the valve casing 28 and to the valve lever 29. The valve control bar 24 is pivotally connected at 30 to the valve lever 29 and is slidably and loosely mounted in an opening 31 in the adjacent side of the casing 1 and is provided with a shouder 32 adapted to hook over the edge 33 in the bottom of 40 the opening 31 for holding the valve 6 in open position against the action of the coiled spring 27.

The coin which is discharged from the hopper 26 enters a V-shaped dipper 34 which is 45 carried by a release lever 35, which release lever is carried by a rock shaft 36 rotatably mounted in bearings of a frame 37. The under side of the dipper 34 is open and straddles the shaft 38, which shaft is rotated by a spring motor 39 through a gear train 40, however the shaft 38 rotates in the direction of the arrow *a*, Figure 7. Dipper lever 35 is normally in the position shown in 50 Figures 7 and 8 and is provided with an adjustable weight 41 whereby its flattened end 42 will be normally forced downwardly for overbalancing the dipper 34 and is in the path of an arm 43 carried by a counter-shaft 44, which countershaft rotates in the direction of the arrow *b*. Disposed above

the dipper arm 35, preferably adjacent the dipper 34 is one of the gear train shafts 45, which shaft is provided with an arm 46, which engages the dipper arm 35 when the gear train is released when a coin is received in the dipper, thereby insuring a rapid downward movement of the dipper into straddling engagement with the shaft 38 for projecting the coin from the dipper into the coin box 47. When the coin leaves 75 the chute hopper 26, it drops into the dipper 34, forces the dipper 34 downwardly and the flattened end 42 of the arm 35 upwardly thereby releasing the shaft 44 and the gear train, which gear train will impart 80 a rotation in the direction of the arrow *a* to the shaft 38. At the same time the shaft 45 will be rapidly rotated thereby forcing the arm 46 into engagement with the dipper arm 35 which will force the dipper 34 downwardly to a position where the shaft 38 will project the coin therefrom. The shaft 44 makes one revolution in the direction of the arrow *b* until the arm 43 engages the flattened portion 42, as the weight 41 immediately 85 rocks the flattened end 42 of the lever 35 downwardly after the coin has been projected out of the dipper by the shaft 38. Shaft 38 is provided with a crank 48 at its outer end, which crank makes a complete 90 rotation, and engages the notch 49 during its rotation of the valve control bar 24, moves the bar in the direction of the arrow *c* until the shoulder 32 receives the bottom edge 33 of the opening 31 in the casing 1, and which shoulder holds the valve 6 in 95 open position, thereby allowing gasoline to be pumped upwardly through the pipe 3 in the usual manner and hold the valve 6 open against the action of the coiled spring 27. 100 As the liquid level in the receptacle 2 rises a float 50 moves upwardly, which float is provided with a downwardly extending rod 51 which terminates in a horizontally disposed arm 52, which is adjustably connected at 53 105 to the slidable frame 8. It will be noted after an operation of the device by a coin, one of the arms 23 will be outwardly disposed as shown in Figure 7, and as the frame 8 is raised by the float 50, said arm 110 23 will engage the bar 24, raise said bar slightly, thereby releasing the shoulder 32 and allowing the coiled spring 27 to move the valve 6 to closed position, thereby preventing further flow of gasoline to the receptacle 2. Arms 23 are located at different 115 distances from the release bar 24 and consequently the liquid level which may be obtained in the receptacle 2 will be positively controlled according to the positions of the arms 23, therefore gasoline to the value of 120 various coin denominations may be allowed to be dispensed. By adjustably connecting the arm 52 at 53 to the frame 8, the frame as a whole may be adjusted to take care of 125 130

fluctuation in the selling price of gasoline which varies a cent or two from time to time.

Coin chutes 25 are provided with openings 55 in their under sides and through which slots slugs or coins of the wrong denominations drop into the slug chute 56 which convey the slugs to a slug receptacle 56^a, therefore a slug or wrong denomination of coin will not operate the machine.

10 It will be noted that as the frame 8 moves upwardly with an operated arm 20 in the position shown in Figure 2, it will engage the hinged plate 57 which rests on the bracket 58, and will move said plate upwardly, and the arm 20 will pass the same. After a valve releasing operation of one of the arms 23, the frame 8 moves downwardly incident to the downward movement of the float 50 during the gasoline discharging operation, and the operated arm 20 will come into engagement with the hinged plate 57, which plate will be held in a horizontal position by the brackets 58 and therefore the arm 20 will be rocked on its pivotal point 20^a to a position where it will not hold the operated shafts 12, 13 or 14 against rotation to normal inoperative position under the influence of the coiled springs 17.

20

25

From the above it will be seen that a gasoline vending device is provided which may be easily applied to a conventional form of dispensing machine and gasoline may be vended in quantities according to the market price at the time.

30 35 To prevent the purchaser from beating the machine by placing a coin in any of the slots 15 and operating the valve 6 to open position and allowing simultaneous discharge of gasoline through the pipe 4, the discharge pipe is provided with a valve 4^a which is open when the valve 6 is closed and is closed when the valve 6 is open, therefore it will be seen that when the lever 24 is moved for opening the valve 6, the valve 4^a will be closed, thereby preventing discharge of gasoline through the discharge pipe 4 until the lever 24 is engaged by one of the pins 23, and the valve 6 closed, at which time the valve 4^a will be moved to open position by the lever 24 to the end of which is pivotally connected at 4^b the valve lever 4^c.

The invention having been set forth what is claimed as new and useful is:—

55 1. The combination with a control valve for a gasoline dispensing tank, spring means for normally maintaining said valve closed, of a slidable frame, a plurality of rods rotatably mounted in said frame, a bar connected to the valve and longitudinally movable, coin controlled means for moving said bar to operative position, said rods being provided with locking pawls, said locking pawls cooperating with shoulders carried by

65 the frame, arms carried by said rods and registering with coin receiving slots, and adapted to be engaged by a coin for rotating said rods, pins carried by said rods and movable to positions in the path of the valve operating bar, and float controlled 70 means whereby said frame may be moved upwardly upon a predetermined liquid level within the tank.

2. A valve operating mechanism for gasoline dispensing machines, said mechanism 75 comprising a casing, a frame slidably mounted in said casing, a plurality of rockable rods in said frame, spring means for holding said rods in inoperative position, latching means carried by said rods and co-operating with shoulders carried by the frame, a valve operating bar carried by the valve and disposed adjacent the rods, a plurality of releasing arms carried by the rods at various distances from the valve bar, 80 arms carried by the rods and normally closing coin receiving slots in the casing and adapted to be engaged by a coin for rotating said rods, a coin controlled spring motor, a crank shaft carried by said motor and co-operating with the bar for moving the same to operative position, means for holding 85 said bar in operative position, said releasing arms being in the path of the operating bar, float means for raising said frame and a 90 hinged tripping member cooperating with the latching means upon the downward movement of the frame for releasing the rods.

95 3. The combination with a valve controlling 100 a flow of liquid to a tank, of coin controlled mechanism, said mechanism comprising an arm carried by the valve, a spring for holding said valve in closed position, a bar connected to the valve arm, a notch carried by said bar and cooperating with a stop for holding the valve in open position, coin controlled mechanism for moving said bar to open position, a slidable frame, a plurality of rods rotatably mounted in the frame, pivoted latches carried by the lower end of said bar and cooperating with stops carried by the frame, releasing arms carried by the rods below the bar and at different distances therefrom, springs carried 105 by said rods for holding the same in inoperative positions, arms carried by the rods and registering with coin receiving slots and adapted to be engaged by a coin for rotating the rods and moving the releasing arms and the pivoted latching members to operative positions, float means for raising the frame, and a hinged releasing member co-operating with the latching members for releasing the same.

110 In testimony whereof I have signed my name to this specification.

ODE TURNER.
